his attorney

UNITED STATES PATENT OFFICE.

ALFRED H. SMITH, OF CHAPPAQUA, NEW YORK.

COMPARTMENT FREIGHT CAR.

Application filed December 21, 1921. Serial No. 524,035.

To all whom it may concern:

Be it known that I, ALFRED H. SMITH, a citizen of the United States, and residing at Chappaqua, in the county of Westchester 5 and State of New York, have invented certain new and useful Improvements in Compartment Freight Cars, of which the following is a specification.

My invention relates to carriers adapted 10 to receive and transport containers holding less than car load lots.

The object of my invention is to provide a carrier and containers of such construction that the containers may be placed on 15 the carrier and maintained against shifting and rocking on the carrier without the aid of any manually operated or movable fastening device.

My invention consists of a carrier having 20 a platform and bulkheads extending vertically from said platform at the sides and ends thereof, bulkheads disposed transversely of the carrier at intervals between which containers may be positioned on the 25 platform of the carrier, with suitable guiding elements fixedly secured to said containers and some of said bulkheads, whereby the containers are guided into position as they are being loaded onto the carrier 30 between said bulkheads.

In the drawings:

Figure 1 is a detail sectional view of a carrier and two containers thereon.

Fig. 2 is a top plan view of a carrier and 35 two containers thereon, the carrier and containers being broken away,

Fig. 3 is a detail vertical transverse section of the carrier.

The reference numeral 1 designates the 40 carrier provided with a platform 2 and side walls 3, which side walls project a substantial distance above the platform of the carrier, and are provided at the top with an angle iron 4 which rigidifies the side 45 walls. End walls of the same construction are provided for the carrier, but are not shown in the drawing.

In the description I shall sometimes refer 50 to the side and end walls as bulkheads.

The carrier is provided at intervals 55 throughout its length with a transverse bulkhead 5, which extends from side wall to side wall and projects upwardly a distance equal to the height of the side walls. Secured at each end and on both sides of the bulkheads are combined spacing and build-

ing elements 6, having flanges 7 which are riveted to the bulkhead 5, and the flanges 8 which are riveted to the side walls of the car, whereby the bulkheads 5 are firmly secured in position. The spacing members 6 have their upper ends beveled inwardly as at 9, which bevel functions as a guide to direct the container being lowered onto a car, into position between the bulkheads. 60 65

The containers 10 are of a suitable construction, designed to securely hold freight, et cetera, each container being provided on each of two walls thereof with a guiding and spacing member 11, having a convex 70 throughout its length, which convex surface is adapted to cooperate with the bevel 9 of the spacing member 6 to guide the container into position between the bulkheads, besides which it fits snugly against the vertical face of the spacing member 6, whereby the container is securely held against 75 rocking and shifting on the platform of the carrier.

While I have selected the embodiment 80 shown for the purpose of illustrating my invention, it will, of course, be understood that changes may be made in the details of the construction without departing from the scope of the appended claims. 85

What I claim is:

1. In a carrier having a platform and bulkheads extending vertically from said platform at its perimeter, bulkheads disposed transversely of the carrier at intervals throughout the length of the carrier between which containers may be positioned on the platform of the carrier, guides secured at each end and to both sides of the transverse bulkheads and terminating in a 95 bevel to guide the containers into position between the bulkheads.

2. In a carrier having a platform, and side and end walls projecting a material distance above the platform, partitions extending transversely of the carrier, spacing elements secured to each side of each partitions and at each end thereof, and secured to the partition and to the side wall of the carrier, and terminating at their upper 100 ends in a bevel to guide containers into position between said partitions and hold them against shifting on the carrier.

3. In a carrier having a platform, and side and end walls projecting a material distance above the platform, partitions extending 110 transversely of the carrier from side

wall to side wall, spacing elements secured to each side of each partition and at each end thereof, a container positioned between each pair of partitions, and guides secured at each lower corner of the container, adapted to engage the spacing elements on the partitions and direct the container into position as it is lowered onto the carrier, also to hold the container against shifting on the carrier.

4. In a carrier having a platform and side and end walls projecting a material distance above the platform, partitions extending transversely of the carrier from side wall to side wall, spacing elements secured to each side and at both ends of the partitions, a container positioned between each pair of partitions, and convex guides secured at each lower corner of the container adapted to co-operate with the spacing ele-

ments to direct the container into position as it is lowered onto the carrier, also to hold the container against shifting on the carrier.

5. In a carrier having a platform and side and end walls projecting a material distance above the platform, partitions extending transversely of the carrier from side wall to side wall, spacing elements secured to each side and at both ends of the partitions and beveled off at the top toward the partition, a container positioned between each pair of partitions, and convex guides secured at each lower corner of the container adapted to co-operate with the spacing elements to direct the container into position as it is lowered onto the carrier, also to hold the container against shifting on the carrier.

In testimony whereof I affix my signature.

ALFRED H. SMITH.
